COMBINED TABLE, CABINET, AND DESK

Charles Samuel Broad, Enfield, England

Application May 24, 1950, Serial No. 10,142
In Great Britain January 2, 1950

Term of patent 14 years

(Cl. D33—19)

To all whom it may concern:

Be it known that I, Charles Samuel Broad, a British subject, residing at Enfield, Middlesex, England, have invented a new, original, and ornamental Design for a Combined Table, Cabinet and Desk, of which the following is a specification, reference being had to the accompanying drawing, forming a part hereof.

Fig. 1 is a front view taken slightly from above of a combined table, cabinet and desk showing my new design;

Fig. 2 is a rear view of the same showing the doors in open position;

Fig. 3 is a perspective view of the cabinet taken from the right as seen in Fig. 1 and with one of the doors shown open;

Fig. 4 is a similar view of the opposite side.

I claim:

The ornamental design for a combined table, cabinet and desk, as shown.

CHARLES SAMUEL BROAD.
